*Hebbard & Polhamus's
Improved Design for Spoons*

New York, 1851.

Patented Jan'y. 6. 1852.

Des. 434

Henry Hibbard & John Polhamus.
Of New York, N.Y.

Letters Patent No 434. Dated Jan 6. 1852.

The schedule referred to in these Letters Patent and making
part of the same.

To all whom it may concern:

To be it known, that we, Henry Hibbard & John Polhamus of city, county & state of New York, have invented or produced a new and ornamental design or configuration for stamping on and ornamenting the handles of spoons, forks, knives or other table cutlery, and we do hereby declare the following to be a full description of the same.

The nature of our invention consists in the ornamenting of the handles of spoons, forks &c, by means of a design formed by the vine & flowers of the convolvulus & so arranged as to form a border around the head of the spoon or fork handle, and a double thread down the length of the handle to the heel which on the obverse side is made to cross each other so as to form diamond squares; and on the reverse side to lose themselves in the lower shoulder at the commencement of the bowl also in ornamenting the heel of the spoon or other article with a convolvulus growing out from between two leaves.

To describe our invention of the new ornamental design more particularly, we will refer to the accompanying drawings of a spoon exhibiting the design and forming a part of this schedule, the same lettered wherever they occur, referring to the same parts.

Figure 1, is a view of the front

or face of a spoon. - Figure 2 is a view of the reverse of back of the spoon.

Letter a is the head of the spoon & letter b, (figure 1,) is a representation of the vine, leaves & flowers of the convolvulus, arranged in such a manner round the edge or margin of the head of the spoon or other article so as to leave an open or shield place for engraving a name or crest.

This vine or device has at the head of the spoon two leaves having a tendril branching down from them and at the left side margin near the head, another leaf, shooting from the vine, which extending down to near the junction with the stem of the spoon ends in a third leaf. On the right side margin of the head piece & branching from the vine is a convolvulus bud, & below the same, two leaves & two convolvulus flowers in full bloom, filling the entire space at the junction of the head of the spoon with the stem and terminating in three leaves between the double row of threads extending down the stem, and crossing each other in diamond form at the heel or shank of the spoon.

Letter c (figure 2) is the vine of the convolvulus surrounding the margin of the reverse side of the head of the spoon or other article, & having at the head two leaves and branching from it, on the left margin a leaf near the upper end, and at a point just at the lower gradation of the swell of the head a second leaf, and then extending down near the junction of the head to the handle or stem, ends in a full blown convolvulus with its mouth opening obliquely across the stem of the spoon.

On the right margin of the head of the spoon branching from the vine, near the upper end is a small leaf, below which a small tendril shoots off toward the

middle of the shield place, & a small convolvulus bud, and terminating in a leaf extending across the lower part of the head of the spoon, so as to give an oval shield space. ~

Down the margin of the stem of the spoon are double rows of thread which are intended as continuations of the vine surrounding the head. ~

At the heel of the spoon are two leaves, having stems loosing themselves down the middle part of the handle, and branching or opening over the swell of the bowl, so as to admit of a full blown convolvulus between them. Below the mouth of the convolvulus are two small leaves, and a tendril extending down towards the centre of the bowl of the spoon. ~

Having now described our invention of a new ornamental design for Spoons, or other articles we will proceed to state what we claim as our invention.:

What we claim therefore is the use of the ornamental design, substantially as herein set forth for the purpose of ornamenting Spoons, Forks or other articles, to which it may be applied. ~

Witness,

J. S. Johnson

Charles L. Parritt,
